(57) **CLAIM**

The ornamental design for a cage of electrical connector, as shown and described.

DESCRIPTION

FIG. 1 is a front, top and left side perspective view of a cage of electrical connector showing our new design;

FIG. 2 is a front plan view of the cage of electrical connector;

FIG. 3 is a rear plan view of the cage of electrical connector;
FIG. 4 is a left plan view of the cage of electrical connector;
FIG. 5 is a right plan view of the cage of electrical connector;

FIG. 6 is a top plan view of the cage of electrical connector;
FIG. 7 is a bottom plan view of the cage of electrical connector; and,

FIG. 8 is a partial enlarged view of portion A of FIG. 1.
The broken dash-dot lines of even length in the drawings illustrate the portions of the cage of electrical connector that form no part of the claimed design. The broken dash-dot lines of uneven length define an area for the enlarged view and the broken dash-dot lines themselves form no part of the claimed design.

The broken lines in the drawings are used for the purpose of illustrating portions of the cage of electrical connector that form no part of the claimed design.
